UNITED STATES PATENT OFFICE.

NICHOLAS SPURGIN, OF OTTAWA, ILLINOIS.

DESIGN FOR A ROOFING-TILE.

SPECIFICATION forming part of Design No. 25,531, dated May 19, 1896.

Application filed April 21, 1896. Serial No. 576,249. Term of patent 3½ years.

To all whom it may concern:

Be it known that I, NICHOLAS SPURGIN, of Ottawa, in the county of La Salle and State of Illinois, have invented a certain new and original Design for a Roofing-Tile; and I do hereby declare the following to be a full, clear, and exact description of the invention, such as will enable others skilled in the art to which it appertains to make and use the same.

10 My invention consists in a design for tiles adapted for roofing or sheathing buildings.

In the accompanying drawings, Figure 1 is a perspective view of my design, and Fig. 2 is a cross-section of the same.

15 The design comprises the longitudinal parallel grooves 1 and 2, formed by the oppositely-inclined portions 3, 4, 5, and 6, the two grooves being connected by a plain strip 7. A second

plain strip 8 projects from the inclined portion 6, and from this strip 8 depends an inclined ledge 9. In the bottom 6 of the groove 1 I provide a longitudinal rib 10, and a similar rib 11 is provided on the under side of the joint between the parts 8 and 9.

Having fully described my invention, what I claim as new, and desire to secure by Letters Patent, is—

The design for a building-tile, substantially as shown and described.

In testimony whereof I have signed this specification in the presence of two subscribing witnesses.

NICHOLAS SPURGIN.
